UNITED STATES PATENT OFFICE.

BENJAMIN LEHR, OF BROOKLYN, NEW YORK, ASSIGNOR TO NEW METHOD SHOE DEVICE CO., INC., OF BROOKLYN, NEW YORK.

DIE FOR CUTTING OUT HEEL SEATS ON SOLES FOR SHOES.

Application filed April 24, 1925. Serial No. 25,598.

My invention relates to dies for cutting out heel seats on soles for shoes preparatory to the attachment of wood heels, and is particularly adapted to that process where-
5 by the heel seat is cut out prior to attaching the sole to the shoe. The prime ob-
ject in view is to provide an economical
method that will effect a reduction in the
time required for the heelng of shoes, and
thus increase production.

A further object of this invention is to
produce an inexpensive die that will give
accurate and uniform results in the heelng
of shoes, and that will be adjustable to dif-
15 ferent sizes of heels.

According to present practice, the heel is
cut out by hand, the method being to first
attach the forward part of the sole to the
shoe, and then cut away a marginal portion
20 of the rear unattached sole. This consti-
tutes a comparatively slow process, as all
hand work is compared to machine opera-
tions. An effort to speed up production
often results in inaccurate work. My in-
25 vention, being essentially in the nature of
a machine or tool, aims to eliminate the un-
certain element inherently connected with
hand work, to produce more uniformly ac-
curate work, and to give greater produc-
30 tion.

In the accompanying drawings:—

Fig. 1 is a plan view embodying my in-
vention.

Fig. 2 is a side elevation of the same.

Fig. 3 is a plan view of a modification of
my invention, without the gage.

Fig. 4 is a plan view of the cut made by
the die of Fig. 1.

Referring to the drawings, 1 is the body
40 of the die, attached to which is the U-shaped
cutting blade 2 and the blades 3 and 4. The
gage 5 consists of an element 6 contain-
ing a slot 7 therein, extending longitudinally
45 in the direction of the sole. Positioned
within this slot is the pointer 8, which is
free to move therein. The calibrated index
9 serves to determine the position of the
pointer 8 to correspond with various sizes
50 of shoes.

When applying the die to an unattached
sole, it will cut out a marginal border 10
at the rear of the sole 11, and will also form
the slits 12 and 13, producing flaps 14 and
15. After the sole is applied to the shoe
55 for heelng, these flaps allow a forward and

backward adjustment of the heel, so as to
render the cut adaptable to heels of dif-
ferent lengths. When the position of the
heel is once determined, the flaps are cut
off at the junction of the heel and the upper
60 of the shoe.

To render the die more accurately adjust-
able to different sizes of heels, the gage
5 is employed. The calibrations on the in-
dex 9 are previously determined by experi-
ment for different lengths or sizes of heels.
65 In the process of operating this die, the
pointer 8 is set to the desired reading pre-
liminary to applying the pressure for cut-
ting. For a short heel the pointer 8 is 70
placed close to the rear of the blade 2, and
for longer heels it is removed farther away
from the blade. The point 16 of the pointer
is then placed at the rear end 17 of the
sole, the die positioned over the heel seat
75 area 18 of the sole, and the pressure ap-
plied for cutting. It will thus be seen that
the longer the heel, the more forward is the
positioning of the die on the sole, and the
nearer the slits 12 and 13 to the front of 80
the sole.

The die 19 with blade 20 is a simplified
modification of my invention, and is par-
ticularly applicable to the process of cut-
ting out the heel seat after the sole is at-
85 tached to the shoe.

While I have herein shown two embodi-
ments of my invention, it is manifest that
many changes may be made in the config-
uration of the die, within the scope of the
90 appended claims.

What I claim is:—

1. A die of the class described contain-
ing a body portion and a cutting edge com-
prising a U-shaped blade with two blades
95 situated one on each side thereof, the said
two blades being transverse to and at an
angle to the sides of the U-shaped blade and
extending outwardly therefrom and posi-
100 tioned away from the extremities of the
two sides of the said U-shaped blade, said
U-shaped and transversely positioned blades
being arranged to remove a marginal bor-
105 der at the rear of the sole and to form for-
wardly extending slits adjacent to the front
part of the heel seat.

2. A die of the class described comprising
a body portion, a cutting edge, and a
gage for adjusting the die for various
110 sizes of heels, the said cutting edge con-

sisting of a U-shaped blade with two blades situated one on each side thereof, the said two blades being transverse to and at an angle to the sides of the U-shaped blade and extending outwardly therefrom and positioned away from the extremities of the sides of the U-shaped blade, the said gauge comprising a suitably attached pointer mov-

able in the longitudinal direction of the sole, and a calibrated index arranged to determine the position of the said pointer with relation to the said U-shaped blade for various sizes of heels.

In testimony whereof I hereby affix my signature.

BENJAMIN LEHR.
